DESIGN FOR A BARRETTE

Nathan L. Solomon, Englewood, N. J.

Application November 20, 1947, Serial No. 142,671

Term of patent 14 years

(Cl. D86—10)

To all whom it may concern:

Be it known that I, Nathan L. Solomon, a citizen of the United States, now residing at Englewood, in the county of Bergen and State of New Jersey, have invented a new, original, and ornamental Design for Barrettes, of which the following is a specification, reference being had to the accompanying drawing, forming part thereof.

I claim:

The ornamental design for a barrette, as shown.

NATHAN L. SOLOMON.
